UNITED STATES PATENT OFFICE

LEWIS COLIN GRANT, OF NEWCASTLE-UPON-TYNE, ENGLAND, ASSIGNOR TO ELECTRICAL IMPROVEMENTS LIMITED, OF NEWCASTLE-UPON-TYNE, ENGLAND, A COMPANY OF GREAT BRITAIN

ELECTRIC CIRCUIT BREAKER

Application filed October 26, 1928, Serial No. 315,305, and in Great Britain November 7, 1927.

This invention relates to electric circuit-breakers, its object being the construction of a circuit-breaker in which the arc formed on the opening of the circuit shall be very quickly quenched.

The invention relates more particularly to circuit-breakers having an arc-quenching device in the form of a series of conducting discs or baffles which surround the movable contact in close proximity to it as it commences its opening movement.

In an electric circuit-breaker according to this invention the arc-quenching device comprises a series of conducting discs or like members insulated and slightly separated from each other, the edges of the discs being closely surrounded by a casing or wall which forms a boundary to the spaces between the discs, the moving contact of the circuit-breaker passing through an aperture in the discs. These discs are conveniently separated and supported by insulating rings or like members which surround the edges of the discs and may constitute the casing or wall referred to as forming the boundary of the spaces between the discs.

The discs may be of appreciable thickness, say for example half-an-inch, and are preferably formed with an annular groove on each face so that when the discs are assembled the narrow spaces between them merge into larger annular chambers formed by the grooves in the neighboring faces.

The discs themselves may have radial passages leading from the central apertures to other passages or openings for the circulation of oil or gaseous products.

In the accompanying drawings,

Figure 1 is a diagrammatic sectional elevation of one construction of circuit-breaker according to this invention,

Figure 2 is a plan view of one of the discs, and

Figure 3 is a perspective view showing diagrammatically a three-phase double-break circuit-breaker having the improved arc-quenching devices.

With reference first to Figure 1, the circuit-breaker represented diagrammatically has a fixed contact A and a movable contact

A¹ mounted in insulators in a tank or casing B. With the details of construction and the connections to the contacts the present invention is not concerned, but it is assumed that the circuit is opened by withdrawing the rod A² and raising the movable contact A¹ into the position shown in dotted lines.

Within the casing B is a series of discs C, say of copper or other conducting material, placed one above the other so that their central apertures C¹ form a passage whose wall closely surrounds the movable contact A¹ as it moves upwards to open the circuit.

These discs C are supported and held by rings of insulating material D secured by bolts E, some of the rings D¹ serving to separate adjacent discs so that narrow spaces F are left between them. These spaces may be quite narrow, i. e. the separation of the discs very small. For instance, supposing the thickness of each disc to be say half-an-inch, the separating spaces might be one-sixteenth of an inch or less.

On each face of each disc an annular groove C² is formed and when the discs are placed in position the grooves on adjacent faces register and form an annular chamber round the edge of the space F. These chambers are closed by the separating rings D¹ in the construction illustrated although that is not necessarily always the case.

Each disc is provided with radial passages C³ leading from the central aperture C¹ to a vertical hole or passage G passing through all the discs and separating rings and affording a path for the circulation of oil if the arrangement is oil-immersed.

Four discs are shown as occupying the lower portion of the tank or casing B. This number may vary and will depend upon the length of the opening movement of the movable contact A¹, the power with which the circuit-breaker has to deal and other factors. A space above the discs beneath the top plate of the tank B forms an expansion chamber. The dimensions of this space may vary and in some instances the discs C may practically fill the casing.

The diagrammatic perspective view forming Figure 3 shows one way in which the im-

- proved arc-quenching devices may be embodied in a three-phase double-break oil-immersed circuit-breaker. Each phase has two fixed contacts A³ mounted on conductors A⁴ in connection with the terminals A⁵.
- 5 Each pair of conductors A⁴ is mechanically connected but electrically insulated by bridging pieces A⁶ and all three sets of fixed contacts are mounted on a bar A⁷ supported by rods A⁸ from the top plate B¹ of the tank B².
- 10 Fixed adjacent to each contact A³ is an arc-quenching device H. The construction of these is not indicated in detail in Figure 3 but it is to be understood that it is similar to the construction described with reference to Figure 1, each arc-quenching device comprising a series of closely spaced and insulated conducting discs having a central aperture closely surrounding the movable contacts. The 15 wall or casing forming the boundary to the spaces between the discs would in Figure 3 be constituted by the supporting and separating rings of insulating material such as are referred to as D and D¹ in Figure 1.
- 20 Each phase switch has two movable contacts represented in Figure 3 at A⁹. These may be formed by the turned-down ends of a common conducting bar and, as indicated in that figure, all three pairs of movable contacts, the pairs being suitably insulated from each other, are supported from a bar A¹⁰ having operating rods A¹¹ which pass out through suitable openings in the tank cover.
- 25 The present invention is not concerned with the details of construction of the parts of the circuit-breaker other than the arc-quenching devices and hence those parts are merely represented diagrammatically.
- 30 The improved arc-quenching device is found to be very efficient in practice, a circuit-breaker of given size breaking satisfactorily circuits of much higher power than can be dealt with by circuit-breakers of the same size and of the usual type. Its efficiency is probably due to a variety of causes, such as the 35 close spacing of the discs, the provision of the enlarged annular chambers into which the spaces lead, and to the radial passages leading into the circulatory holes or passages through 40 the discs and their supports.
- 45 An important factor is probably that the spaces between the discs are not open on their outer edges to the oil or other fluid in the circuit-breaker casing but are surrounded by 50 the wall formed by the insulating rings or by some other enclosing member, as for instance the casing of the circuit-breaker itself which in some constructions, such as that 55 illustrated in Figure 1, is in close proximity to the arc-quenching device.
- 60 What I claim as my invention and desire to secure by Letters Patent is:—
1. In an electric circuit-breaker the combination with a moving contact, of an arc-quenching device comprising a series of con- 65 ducting discs insulated from one another and separated from one another by a distance which is small relative to their thickness, the edges of the discs being closely surrounded by a casing forming a boundary to the spaces between the discs, and the discs being provided with aligned apertures through which the moving contact passes. 70
2. In an electric circuit-breaker the combination with a moving contact, of an arc-quenching device comprising a series of conducting discs through which the moving contact passes and a series of insulating rings for supporting said discs so that they are insulated from one another and are separated from one another by a distance which is small relative to their thickness, said insulating rings forming a wall surrounding the edges of the discs. 75
3. In an electric circuit-breaker the combination with a moving contact of an arc-quenching device comprising a series of conducting discs insulated and slightly separated from one another each disc being formed with an annular groove on each face such grooves in adjacent discs cooperating to form a larger annular chamber in the narrow space between said adjacent discs, the edges of the discs being closely surrounded by a casing forming a boundary to the spaces between the discs and the discs being provided with aligned apertures through which the moving contact passes. 80
4. In an electric circuit-breaker the combination with a moving contact of an arc-quenching device comprising a series of conducting discs having aligned apertures through which the moving contact passes and a series of insulating rings for supporting said discs so that they are insulated and separated from each other and for forming a wall surrounding the edges of the discs, each disc being formed with an annular groove so that when the discs are assembled the narrow spaces between them merge into larger annular chambers. 85
5. In an electric circuit-breaker the combination with a moving contact of an arc-quenching device comprising a series of conducting discs having aligned central apertures through which the moving contact passes and radial passages leading from the central aperture to other passages or openings for the circulation of oil or gaseous products, discs being insulated and slightly separated from each other and the edges of the discs being closely surrounded by a casing forming a boundary to the spaces between the discs. 90
6. In an electric circuit-breaker the combination with a moving contact of an arc-quenching device comprising a series of conducting discs having aligned central apertures through which the moving contact passes and radial passages leading from the 95

central aperture to other passages or openings for the circulation of oil or gaseous products and a series of insulating rings for supporting said discs so that they are insulated and 5 separated from each other and for forming a wall surrounding the edges of the discs.

7. In an electric circuit-breaker the combination with a moving contact of an arc-quenching device comprising a series of conducting discs having aligned central apertures through which the moving contact passes and radial passages leading from the central aperture to other passages or openings for the circulation of oil or gaseous products and a series of insulating rings for supporting said discs so that they are insulated and separated from each other and for forming 15 a wall surrounding the edges of the discs, each disc being formed with an annular groove so that when the discs are assembled the narrow spaces between them merge into larger annular chambers.

8. An electric circuit-breaker comprising a tank, insulating oil in said tank, a fixed contact mounted therein and a moving contact supported thereby, a series of conducting discs having aligned apertures through which the moving contact passes and a series of insulating rings for supporting said discs in the 25 tank so that they are insulated from one another and separated from one another by a space in which the oil circulates, the tank being formed so that it surrounds closely said insulating rings.

35 In testimony whereof I have signed my name to this specification.

LEWIS COLIN GRANT.
